[57] CLAIM

The ornamental design for a combined compact disc player and radio receiver, as shown and described.

DESCRIPTION

FIG. 1 is a right side view of a combined compact disc player and radio receiver, showing my new design;

FIG. 2 is a left side view thereof;

FIG. 3 is a top view thereof;

FIG. 4 is a front view thereof; and,

FIG. 5 is a rear view thereof.

The undisclosed bottom view of the combined compact disc player and radio receiver forms no part of the claimed design.
